UNITED STATES PATENT OFFICE.

THOMAS F. MASON, OF VARNER, MISSOURI, ASSIGNOR OF ONE-HALF TO
JOHN BOST, OF SAME PLACE.

LOCOMOTIVE TURN-TABLE.

SPECIFICATION forming part of Letters Patent No. 669,844, dated March 12, 1901.

Application filed August 16, 1900. Serial No. 27,061. (No model.)

To all whom it may concern:

Be it known that I, THOMAS F. MASON, a citizen of the United States, residing at Varner, in the county of Ripley and State of Missouri, 5 have invented certain new and useful Improvements in Locomotive Turn-Tables; and I do declare the following to be a full, clear, and exact description of the invention, such as will enable others skilled in the art to which 10 it appertains to make and use the same.

My invention relates to improvements in locomotive turn-tables, and has for its object, primarily, to provide a turn-table which will be automatically operated by the weight of 15 the locomotive thereon.

A further object of the invention is to provide a turn-table of this character having a system of gearing for automatically releasing the latch and swinging the turn-table, combined with a retracting device for automatically resetting the gearing for further operation.

A still further object of the invention is to provide a safety device for preventing the retraction of the latch mechanism and release of the turn-table until the gearing is primarily operated by the locomotive.

With these and other minor objects in view the invention consists of certain novel features of construction, combination, and arrangement of parts, as will be hereinafter more fully described, and particularly set forth in the appended claims.

In the accompanying drawings, Figure 1 is 35 a top plan view of a locomotive turn-table embodying my invention. Figs. 2 and 3 are elevational views looking toward opposite sides of the turn-table and showing the same in its normal position. Fig. 4 is a vertical longitudinal section on line 4-4 of Fig. 1. Fig. 5 is a vertical transverse section on line 5-5 of Fig. 1. Fig. 6 is a view similar to Fig. 4, showing the movable bridge or rail sections depressed and the safety-catch device retracted. 40 Figs. 7 and 8 are detail views showing, respectively, the position of the safety-latch-controlling mechanism when the latch is retracted and projected.

Referring now more particularly to the 45 drawings, wherein like reference-numerals designate corresponding parts throughout the

several views, the numeral 1 designates a base of any preferred construction and which may form the bottom of a pit of the usual type or be mounted in any preferred way, and 2 a 55 pillar carrying a latch-bar 3, having a keeper or opening 4 for the reception of the latch, hereinafter described, which holds the table from turning. The pillar may be mounted, as shown, upon the base, or it may form part 60 of the masonry of a pit, as desired. Projecting upwardly from the base is a post 5, which enters a socket 6 in the bottom of the turn-table 7, and upon this post is revolvably mounted a spool 8, between which and the base and 65 turn-table are applied antifriction-balls 9, running in grooves therein to adapt the turn-table to move with freedom. The turn-table is also provided on its under side with ball-bearing rollers 10, which traverse the base and 70 hold the turn-table properly supported. From opposite sides of the turn-table rise two standards or pillars 11, upon which is mounted a bridge 12, which supports a platform 13, and in the turn-table is mounted a shaft 14, carrying 75 at one end a spur traction-wheel 15, which meshes with a circular rack 16, arranged upon the base concentric with the post 5. The opposite end of this shaft carries a pinion 17, which receives motion from a train 80 of gears 18, 19, and 20, carried by shafts 21 and 22, journaled in ball-bearing boxes 23 in a frame 24, rising from the turn-table on one side of the bridge 12.

To the shaft 22 of the upper gear-wheel 85 20 is fixed an oscillating crank-arm 24, from which projects a lateral wrist-pin or spindle 25, located above the bridge 12. Upon this pin or arm is pivotally mounted, by means of straps 26, the inner end of one of two co-operating movable bridge or rail sections 27 and 28, united by hinges or pivots 29 at their inner ends and forming two inclined planes carrying track-rails 30 for the locomotive to run upon. The inner ends of these bridge-sections are normally held elevated, and their outer ends rest upon rollers 31, mounted upon bearing-plates 32 at the outer ends of the fixed bridge 12, which plates project above the rollers to form stops to hold the said outer ends 90 of the movable bridge-sections from lateral play. A post or standard 33 rises from the

platform 13 on the opposite side of the bridge 12 from the gearing-frame 24, and carries at its upper end a pulley 34, over which passes a cord, wire, or cable 35, secured at one end to 5 a link 35^a, connected to the spindle 25, and at the other end to a counterbalancing-weight 36, the function of which is to restore the parts to their normal position upon the operation of the turn-table.

10 The turn-table is held from movement until operated by a latch 37, mounted to slide in a keeper 38, secured to one side of the fixed bridge 12, adjacent to the post 33, and this latch is provided with a rearwardly-projecting arm 39, which is acted upon by a spring 40, arranged in a casing 41, to normally hold the latch projected. The latch is also provided with an upwardly-extending lug 42, to which is connected the forward end of a rod 20 43, the rear end of which is connected to a crank-pin 44 upon a ratchet wheel or disk 45, carried by a shaft 46, mounted in a ball-bearing bracket or bearing-box 47 upon said bridge 12. The ratchet-wheel is operated to retract 25 the latch by dogs 48, mounted upon a bearing-plate 49, secured to the movable inclined bridge-section 27, said plate being provided with stop-shoulders 50 to hold the dogs in engaging position and prevent rearward movement thereof.

The operation of the parts thus far described is as follows: Assuming that the parts are in the position shown in Figs. 2 and 3, with the inclined bridge-section 27 in line with the 35 track, the locomotive is run upon said bridge-section 27, and the inner ends of the two bridge-sections 27 and 28 are gradually depressed by the weight thereof until lowered to a horizontal position, when the locomotive 40 may run from one onto the other. When the bridge-sections are part-way lowered--say depressed one-fourth or one-third of the distance--the dogs 48 are caused to engage the ratchet-wheel 45 and partially rotate said 45 wheel in one direction, (to the left in Fig. 3,) and thereby draw the rod 43 rearwardly to retract the latch against the tension of its spring. Upon the retraction of the latch the further movement of said bridge-sections 50 causes the spindle 25 to be also depressed and to turn the crank-arm 24, thereby communicating motion to the train of gears which rotate the shaft 14 and cause the traction-wheel 15 to run upon the rack 16 and turn the turn-table one-half revolution, so as to reverse the 55 position of the two inclined bridge-sections 27 and 28 and turn the locomotive around. The locomotive may thereupon run off the bridge-section 28 upon the track, and when said 60 bridge-sections are relieved of the weight thereof the weight 36 elevates the free ends of the same and communicates motion to rotate the gearing in the reverse direction and restore the turn-table to its original position. 65 The latch upon being released by the disengagement of the dogs from the ratchet-wheel again engages the keeper 4 and locks the

turn-table against rotation. Figs. 3 and 4 of the drawings necessarily show the sections 27 and 28 inclined to a greater extent than 70 required in order to more clearly disclose the structure of the parts thereunder; but it will be understood that in practice only a slight inclination of said sections is necessary to secure the effective operation of the apparatus. 75 The locomotive may be run upon the section 27 at ordinary yard speed, which will enable it, with its tender, to pass fully on said section before the sections have been depressed to the extent sufficient to operate the latch. The 80 rail-sections may, however, be so constructed as to move only when the full weight of the locomotive and tender rests upon the section 27, although a preliminary downward movement of the sections may take place without 85 liability of accident, provided such movement is insufficient to effect the operation of the latch mechanism until the locomotive and its tender occupy the said section 27. When the locomotive is fully run upon the inclined 90 section 27, it is instantly brought to a stop by applying the brakes, and as the depression of the rail-sections is then quickly effected all liability of a backward movement is avoided. If, however, the inclined sections should be 95 tardy in action, the engineer, having complete control of the locomotive, may readily prevent any tendency of the same to run backward.

In order to prevent retraction of the latch 100 and release of the turn-table before the gearing is primarily operated, so as to insure safety, I provide mechanism consisting of a pivoted bell-crank lever 51, located adjacent to the post 33 and having one of its arms connected by jointed links 52 and 53 to the spindle 25. To the opposite arm of the bell-crank lever is attached a guide-plate 54, between which and the arm a pin 55 extends and is adapted to be engaged by the notched or hooked free end 56 of a locking-lever 57. This lever is connected at its opposite or outer end to the crank-pin 44 of the ratchet-wheel, and its free end is normally held down by a spring 58. When the turn-table is locked, the bell-crank lever is drawn upon to hold the locking-pin 55 into position to engage the notched 110 end of the lever 57, as shown in Fig. 8; but when the inclined bridge-sections 27 and 28 are depressed the links 52 and 53 are forced 115 downward and the pin 55 moved rearwardly and downwardly, leaving the notched end of the lever 57 free to slide inwardly over the same upon the movement thereof by the dogs 120 engaging and rotating the ratchet-wheel, as 125 shown in Fig. 8.

From the foregoing description, taken in connection with the accompanying drawings, the construction and mode of operation of the invention will be clearly understood without a more extended description and the advantages thereof will be obvious. Changes 130 in the form, proportion, and details of construction of the several parts of the turn-table

ble may of course be made within the scope of the invention without departing from the spirit thereof.

Having thus fully described my invention, 5 what is claimed, and desired to be secured by Letters Patent, is—

1. In a turn-table, the combination of two inclined rail or bridge sections, gearing operated by the depression of said sections to 10 operate the turn-table, a latch device for securing the turn-table, and means for automatically retracting said latch device upon the depressions of the bridge-sections, substantially as set forth.
- 15 2. In a turn-table, the combination of a base carrying a rack, a turn-table, a shaft upon the turn-table carrying a traction-wheel meshing with the rack, a train of gears for operating said shaft, and inclined rail or 20 bridge sections adapted when depressed to impart motion to said train of gears, substantially as set forth.
- 25 3. In a turn-table, the combination of depressible rail-sections, operating means, and a latch device automatically retracted by the depression of said rail-sections to release the turn-table, substantially as set forth.
- 30 4. In a turn-table, the combination of inclined pivoted bridge or rail sections, operating means, a latch retracted by the depression of said rail-sections, and a safety device to prevent retraction of the latch before said sections are depressed to the desired extent, substantially as set forth.
- 35 5. In a turn-table, the combination of pivoted inclined rail-sections, a spring-actuated latch, a ratchet-wheel and connections to project the latch, and dogs on one of said sections to actuate the ratchet-wheel, substantially as set forth.
- 40 6. In a turn-table, the combination of pivoted inclined rail or bridge sections, operating means, a spring-actuated latch, a ratchet-wheel for retracting the latch, dogs for oper-

ating the ratchet-wheel to retract the latch, 45 a locking-lever for preventing movement of the ratchet-wheel before the bridge-sections are depressed to the desired extent, and locking means moved into and out of engagement with the lever by the movements of the bridge- 50 sections, substantially as set forth.

7. In a turn-table, the combination of depressible rail-sections, operating means, and a latch device automatically retracted when the locomotive runs upon a rail-section to release the turn-table, substantially as set forth. 55

8. In a turn-table, the combination of depressible rail-sections, operating means, an automatically - retracted, spring - projected latch, and a safety device operated by the rise 60 and fall of said rail-sections to engage and release the latch, substantially as set forth.

9. A turn-table comprising movable rail-sections, operating mechanism, means for locking and releasing the turn-table, and re-tracting mechanism, which elements are entirely automatic in character and operated solely by the presence or absence of the weight of the locomotive, substantially as set forth. 65

10. In a turn-table, the combination of a base, a rack thereon, a shaft upon the turn-table carrying a gear meshing with the rack, a train of gears for operating said shaft, depressible rail-sections for imparting motion 75 to said train of gears, automatic means for locking and releasing the turn-table, and re-tracting means for restoring the turn-table and parts to their normal positions, substantially as set forth. 80

In testimony whereof I have hereunto set my hand in presence of two subscribing witnesses.

THOMAS F. MASON.
